UNITED STATES PATENT OFFICE

2,558,600

ILLUMINATED LAMP BASE

Thomas Woodrow Wilson, Millville, N. J.

Application May 31, 1946, Serial No. 673,284

2 Claims. (Cl. 240—10)

1

This invention relates to lamps, and particularly to a lamp formed of a glass or crystal element forming a base that may be used as a lamp independently or in combination with a reading lamp on a pedestal or stand. In particular, the invention relates to a crystal body wherein light rays from a lamp bulb therein show through two points only on the surface thereof, such as the eyes of an animal in the form of which the body may be made.

The invention also contemplates a reading or desk lamp at the upper end of a stem extending upward from the body with a light bulb or bulbs therein in which the shade thereof represents a mushroom or device that harmonizes with the body.

To concentrate the light rays so that they emanate from two light spots only, the surface of the crystal body or base is reflecting or opaque.

To further improve the lamp, sections of the body, such as the feet or ears of an animal which it may be formed to represent, may be clear, translucent, or covered with thin or translucent material. When the body is formed to represent a tree stump, knots or surfaces from which branches or the like may be cut, may be translucent, colored, or clear.

The base or body may be used independently, and may be placed on a table or stand, or may be used as a door-stop. When it is desired to provide a dim light in a room or house, the upper light may be extinguished, and with the light beams emanating from two points only of the base, it will be difficult for an intended intruder to ascertain whether or not the room is occupied.

The invention also contemplates a combination lamp in which a reading lamp is positioned above a base that also forms a lamp, and the base is provided with a combination switch by which the bright reading lamp may be lighted, or light may emanate only from two points or eyes of the base, or both the reading lamp and the base may be lighted.

The invention includes, in particular, a lamp base having a cavity in the underside thereof in which substantially the whole of the outer surface is opaque, having light openings only at points therein, such as the eyes, when the base simulates an animal, fowl, or the like.

Another object is to provide a unique lamp in which light emanates from a point or a plurality of points on the surface thereof only.

Another object is to provide a lamp in which light emanates from points only, which may be combined with a reading lamp or the like.

2

A further object is to provide a combination lamp of ornamental design in which the base constitutes a complete lamp and may be used independently of the reading lamp.

With these and other objects in view, the invention embodies a lamp formed of a solid block of transparent material, such as a crystal, in which the outer surface is diffused or opaque, with the exception of certain points therein, and the lamp bulb is incorporated in a cavity and positioned for reflection of the light rays thereof through the crystal or body, and to the points on the surface that are not opaque.

The invention also embodies the relatively solid or crystal base in combination with a desk or reading lamp having a stem extending upward from the base, and a light bulb or bulbs in a shade mounted on the stem.

For a full and more complete understanding of the invention, reference may be had to the following description and accompanying drawing, wherein:

Figure 1 is a view showing a side elevation of the combination lamp, with the light indicated in dotted lines.

Figure 2 is a cross section through the base portion of the lamp.

Figure 3 is a view looking upward showing the cavity in the base of the lamp.

Figure 4 is a view showing a front elevation of the lamp.

Referring now to the drawing wherein like reference characters denote corresponding parts, the lamp of this invention comprises a substantially solid base element 10, a stem 11, and a lamp shade 12.

The base 10 is a substantially solid crystal, being formed of molded glass or of transparent or partially transparent plastic, and whereas the design shown in the drawing represents a frog, it may be formed to represent other animals, fowls, objects, or the like.

The element 10 is molded or formed with a cavity 13 in the under surface, and the entire outer surface, with the exception of points such as the eyes 14, may be coated or treated so that it is opaque or at least translucent. The continuous opaque outer surface may also be broken at points, such as the claws 15, and these surfaces may be translucent wherein a diffused light will show therethrough. Similar translucent areas may also be provided to accentuate different parts of the animal or the like, such as the shoulders, elbows, ears, nose, or the like.

With a light bulb 16 positioned in the cavity

13 in the lower side of the base, light will be reflected through the crystal-like material, and will show only at the eyes or other clear points, and with the eyes providing the only clear points, two beams of light only will be visible. With the base placed in a darkened room, a very unusual effect will be produced as the two beams of light emanating from the eyes will be the only source of illumination of the room. The illuminating characteristics thereof may be varied by providing partially transparent areas at different points. To further produce various lighting effects, parts of the surface may be colored and light emanating from different areas may travel in different directions.

A combination light switch 17 adapted to be operated by a button 18 may be located in the base, and this may be connected by suitable wires 19 to the light 16 and by wires 20 to a light 21 in the lamp formed by the shade 12. The light 21 may be mounted by a socket 22 at the upper end of the stem 11, and the shade 12 may also be supported at the upper ends of the stem by a bracket 23.

The stem 11 is preferably formed of a tube 24 which may be of glass, plastic, metal, or any material, and may be transparent or opaque, as may be desired. The tube extends upward from an opening 25 in the base 10, and the wires 20 extend upward therethrough to the socket 22 of the light 21. The lamp is provided with supply wires 26 that extend from the switch 17 through a slot 27 in the rear portion of the base 10. By operating the button 18, the lamp 16 only may be lighted to illuminate the base, or the lamp 21 may also be lighted to provide a reading lamp, as may be desired. Any conventional form of three-way switch may be used, and this may be operated by any means. Alternatively the device may be wired so as to permit the lighting of lamp 21 alone.

The shade 12 in the design shown represents a mushroom with the support 11 illustrating the stem. It will be understood, however, that the shade 12 may be of any shape or design, and is preferably designed to correspond with the animal, fowl, or the like represented by the base.

It will also be understood that, whereas one lamp only is shown in the shade, a plurality of lights may be used therein, if desired.

While a preferred specific embodiment of the invention is hereinbefore set forth, it is to be clearly understood that the invention is not to be limited to the exact construction illustrated and

described because various modifications of the details may be provided in putting the invention into practice within the purview of the appended claims.

5 What is claimed is:

1. In combination, a lamp base comprising a solid block of transparent material having a flat bottom surface formed with a recess with the remainder of the block having a contour in simulation of a natural object, an opaque coating on the major portion of said contour leaving uncoated portions, an electric light bulb in said recess, a control switch for said bulb in said recess, and an operating member for said switch 10 extending through an opening in said block.

2. In combination, a lamp base comprising a solid block of transparent material having a flat bottom surface formed with a recess with the remainder of the block having a contour in simulation of a natural object, an opaque coating on the major portion of said contour leaving uncoated portions, an electric light bulb in said recess, a stem having its lower end anchored in said block and upstanding therefrom, an electric 20 light bulb carried by said stem at its upper end, a lamp shade also carried by said stem and disposed over the bulb carried thereby, a control switch for both of said bulbs, and an operating member for said switch extending through an opening in said block.
